FLOORING SECTION FOR PARQUET FLOORS

Jerome Scheller, Rte. 1, Peach Orchard, Ark. 72453

Filed Apr. 19, 1965, Ser. No. 84,855

Term of patent 14 years

(Cl. D13—1)

Fig. 1

Fig. 2

Fig. 3

FIG. 1 is a top perspective plan view of a flooring section for parquet floors formed in accordance with the design of this invention.

FIG. 2 is a bottom perspective plan view of the hexagonal section of parquet floors as shown in FIG. 1.

FIG. 3 is a perspective plan view of one of the individual block segments of trapezoidal shape from which the flooring sections are composed.

I claim:

The ornamental design for a flooring section for parquet floors, substantially as shown and described.
